UNITED STATES PATENT OFFICE.

ARTHUR A. WRIGHT, OF MOULTON, IOWA.

JOURNAL-BOX.

1,146,831.

Specification of Letters Patent. Patented July 20, 1915.

Application filed February 14, 1914. Serial No. 818,719.

To all whom it may concern:

Be it known that I, ARTHUR A. WRIGHT, a citizen of the United States, residing at Moulton, in the county of Appanoose and 5 State of Iowa, have invented new and useful Improvements in Journal-Boxes, of which the following is a specification.

This invention relates to improvements in journal boxes for railway cars, heavy machinery and the like, and the object of the 10 invention is to provide a simple and comparatively inexpensive device of this character, which will be strong and durable and which will effectively exclude water and 15 dust, and which presents novel means for preventing the anti-frictional rolls from becoming twisted or grooving the end of the journal box.

The invention further consists in providing 20 a journal box with a detachable lubricating pocket or chamber which may be readily applied to the journal box to supplement a worn or damaged pocket.

To these and other ends the invention 25 resides in the novel construction of elements and their assemblage in operative combination as will be hereinafter fully described and claimed.

Figure 1 is a longitudinal sectional view 30 of my improved journal box showing the same in position upon an axle, and Fig. 2 is a transverse vertical section upon the line 2—2, of Fig. 1.

In the accompanying drawing, the 35 numeral 1 designates my improved journal box provided with a central longitudinal opening 2, cylindrical in a cross section and having substantially rectangular longitudinally extending channels 3 communicating with the central opening 2 and which are arranged at points diametrically opposite the center of the opening 2. The journal box is also provided with a series of vertical openings or orifices 4, arranged in a plane and 40 communicating with the rectangular longitudinal channels 3 of the journal box. A bearing box comprising two semi-cylindrical sections 5 and 6 having flanges 7 and 8 upon each of their ends and a longitudinal flange 45 9 upon each of their longitudinal edges is adapted for reception within the opening 2 formed within the journal box. The flanges 9 each project the same distance from both the outer and inner edges of each of the

members comprising the bearing box and 55 the said flanges fully fill the channels 3, having their outer edges contacting with the outer walls provided by the said channels, so that neither of the sections of the bearing box may extend beyond the other so that a 60 perfect register of the sections of the box is maintained and consequently a smooth inner periphery of the box is assured. Suitable 65 openings 10 are provided upon the longitudinal flanges 7 and 8 of the bearing box, and are adapted to align with the vertical openings 4 of the journal box, and these openings are adapted for the reception of the bolts 11 having threaded extremities for 70 the reception of nuts or other suitable retaining elements 12, whereby the boxing may be securely retained in position within the longitudinal opening 2 of the journal box. Suitable anti-frictional rollers 13 are 75 adapted to be received within the chamber formed by the flanges 7 and 8 upon the ends of the box sections 5 and 6, and are adapted to bear upon an axle 14 as clearly illustrated in the drawing.

A lubricating pocket 15 having a hinged 80 cover 16, is adapted to be secured upon the face of the journal box 1, through the medium of securing elements 17. This lubricating pocket serves a double purpose as it provides means whereby pockets worn or 85 damaged may be readily and easily replaced upon a journal box, thus preventing the entire discarding of a damaged journal box and the replacing of the same by an entirely 90 new box, and it also serves for the allowance of the ready insertion of the bearing box within the journal by merely removing the lubricating pocket from the box and replacing it after the bearing box has been inserted within the journal box. 95

From the foregoing description it will be noted that I have provided an improved journal box for cars or the like which is extremely simple, comparatively inexpensive as well as being strong and durable, and which allows for the ready insertion or removal of anti-frictional rolls and a bearing for the roll, and which is provided with a removable lubricating pocket which may be readily replaced when worn or damaged without interfering with the remainder of the journal box. 100 105

While I have described the preferred embodiment of my invention minor details of

construction may be resorted to without departing from or sacrificing any of the advantages of the invention.

Having thus described the invention what is claimed as new is:—

- 5 A journal box having a cylindrical opening, the diametrically opposite walls of which have longitudinally extending substantially rectangular channels, a bearing
- 10 box comprising two semi-cylindrical members arranged within the opening, said bearing box having end flanges and having their longitudinal edges formed with outturned substantially rectangular flanges which rest
- 15 one upon the other and which are received within and fully fill the substantially rec-

tangular channels to maintain the perfect register of the sections of the bearing box when arranged within the opening in the journal box, securing members passing 20 through the journal box and through the said flanges of the bearing box, and the said flanged bearing box providing a cage for anti-frictional rollers for the axle upon which the box is arranged. 25

In testimony whereof I affix my signature in presence of two witnesses.

ARTHUR A. WRIGHT.
